UNITED STATES PATENT OFFICE.

WALTER D. GILES, OF LEESVILLE, LOUISIANA.

WELL RIGGING.

Application filed February 12, 1926. Serial No. 87,964.

This invention relates broadly to improvements in well rigging and has more particular reference to novel and simplified means for removing rods and tubing from wells.

5 The primary object of the present invention is to provide a device of the nature stated which will not only raise the rods or tubing from within the well but which will also lower the same and carry them exteriorly of the derrick.

Another object of the present invention is to provide such a device which will save both time and labor in the pulling of rods and tubing from wells thereby increasing the 15 production of the wells at a reduction in the cost of operating.

Another object of the invention is to provide such a device of the nature stated which is extremely simple in its construction, 20 strong, sturdy and durable; efficient and reliable in its operation and well designed for the purposes for which it is intended.

Numerous other objects and advantages of the present invention will become more readily apparent during the course of the following description when taken in connection 25 with the accompanying drawings:

In the drawings, forming a part of this application and wherein for the purpose of 30 illustration has been disclosed a preferred embodiment of the present invention:

Figure 1 is a side elevation of an improved well rigging constructed in accordance with the present invention.

35 Figure 2 is a top plan view thereof with a portion of the derrick broken removed.

Figure 3 is an enlarged elevation of the improved reel used in connection with the present invention.

40 Figure 4 is a sectional view on line 4—4 of Figure 2.

Figure 5 is a sectional view on line 5—5 of Figure 1.

Reference now being had more particularly to the accompanying drawings wherein similar characters of reference denote corresponding parts throughout the several views, it will be clearly seen that in carrying the present invention into practice, there are 45 provided a plurality of supporting blocks 9 carrying at their upper ends the transverse sills 10 supporting the elongated horizontally disposed platform 11 one end portion thereof being transversely enlarged as indicated at

12 and rising from this enlarged end portion 55 12 is a derrick designated as a whole by the numeral 13.

Secured to the top 14 of the derrick 13 are the spaced bearing blocks 15, 16 and 17 within which are journaled the horizontal 60 shafts or rods 18 and 19 on which are mounted the pulleys 20 and 21 respectively, these pulleys being positioned directly above openings 22 and 23 formed in the said top 14 of the derrick.

Carried by the enlarged end portion 12 of the platform 11 immediately adjacent the outer end thereof, are the spaced vertically disposed bearing blocks 24 and 25 and extending between and secured within these 70 bearing blocks is the rod or shaft 26 on which is rotatably mounted the reel designated generally by the numeral 27, said reel being divided into sections 28, 29 and 30 by the radiating spokes 31, 32 and 33 or by 75 means of any suitable guard plates. Carried by one end of the reel 27 is a drive pulley or the like 34 about which is adapted to be trained a drive belt or chain 35 having connection with a suitable driving engine, not 80 shown.

Wound around the section 28 of the reel 27 is one end of the cable 36, said cable passing upwardly through the top 14 of the derrick and over the pulley 20 supported thereby.

Secured to the free end of the cable is a clamping member 37, said clamping member comprising a tubular sleeve 38 and pivoted to the upper edge of the said sleeve, intermediate their ends, are the oppositely positioned gripping jaws 39 having pivoted to their outer ends, the links 40, said links being secured at their upper ends as at 41 to the said cable 36.

Wound about the section 29 of the cable 27 95 but in an opposite direction to the cable 36 is a similar cable 42, said cable passing upwardly through the top 14 of the derrick and over the pulley 21, the free end of the cable having secured thereto a clamping member 100 43 which is similar in construction to the clamping member 37.

Positioned at the forward end of the platform 11 are the spaced bearing blocks 44 and 45 within which is journaled the shaft 105 46 carrying the pulley 47 and trained around this pulley and the section 30 of the reel 27 is the endless cable 48. Secured over the

endless cable 48 are the tubular sleeves or the like 49 and 50 to which are pivotally connected as at 51 and 52, the hooks 53 and 54, each of said sleeves being provided with 5 a suitable clip or the like 55 to which the said hooks may be detachably secured when they are not in use.

Carried by the platform 11 are the spaced 10 guards 56 and 57 and by reference to Figure 4, it will be clearly seen that each of the said guards is of substantially inverted V-shaped formation having the substantially vertical leg 58 and the slanting leg 59, both of said legs having the feet 60 by means of 15 which the same may be secured to the platform 11. The lower run 61 of the endless cable 48 is arranged to pass between the legs 58 and 59 of the guards while the upper run 62 of the said endless cable is positioned 20 exteriorly of the guard and this construction is provided so as to prevent the rods being removed from the well from crowding the cable as they are lowered.

In the operation of the present invention, 25 it will of course be understood that as the reel 27 is rotated, in one direction, the cable 36 will be wound about the reel while the cable 42 is unwound, and as the reel is rotated in the opposite direction, the cable 42 30 will be wound about the reel while the cable 36 will be unwound. Also, that the endless cable 48 travels at all times in the direction of rotation of the reel.

The numerals 63 and 64 denote two rod 35 or tube sections and it will be seen upon reference to Figure 1 that the section 63 has been removed from the well and is held thereabove by the clamping member 43 while the section 64 is engaged by the clamping 40 member 37 and is ready to be pulled. It will also be noted that the hook 54 is engaged with the lower end of the section 63.

Let us now assume that power is applied 45 to the drive pulley 34 through the medium of the belt 35 and the reel 27 is caused to rotate in an anti-clockwise direction. This rotation will cause the cable 36 to be wound upon the reel 27, the cable 42 to be unwound therefrom and the endless cable 48 to be moved in an anti-clockwise direction. As 50 the cable 36 is wound upon the section 28 of the reel, the rod or tube section 64 will be pulled from the well to assume the position of the section 63 shown in Figure 1. Simultaneous with this operation, the cable 55 42 will be unwound from the section 29 and the endless cable 48 will move in an anti-clockwise direction with the result that the hook 54 which had been previously engaged 60 with the section 63 will act to draw the same outwardly so that the section will assume a horizontal position. When the section 65 is clear of the derrick, it can be detached from the clamp 43 and moved to any suitable place.

When this operation has been completed, the section 64 will be in the position of the section 63 and the clamp 43 which has been lowered, can then be secured to the next section to be pulled. The hook 53 is then 70 secured to the bottom of the section 64 and the reel is operated in the opposite or clockwise direction with the result that the cable 42 will be wound upon the reel to pull from the well the next section while the cable 36 75 will be unwound and the endless cable 48 moving in a clockwise direction will draw the section outwardly.

From the above, it is thought that the construction and operation of the invention 80 will be sufficiently clear to enable others skilled in the art to make and use the same, and that while there has been disclosed a preferred embodiment of the same it is to be understood that various changes in the 85 details of construction thereof may be found desirable and that any such changes as properly fall within the scope of the appended claims may be resorted to without departing from or exceeding the scope of 90 the invention.

What is claimed is:

1. A well rigging of the class described including means for simultaneously raising and lowering sections of rods or tubing, and means operated by the first mentioned means for carrying away the section being lowered. 95

2. A well rigging of the class described including a derrick, means associated with the derrick for simultaneously raising and 100 lowering sections of rods or tubing, and means operated by the first mentioned means for simultaneously carrying the section being lowered exteriorly of the derrick.

3. A well rigging of the class described 105 including a derrick, means associated with the derrick for simultaneously raising and lowering sections of rods or tubing, means operating simultaneously with the first mentioned means for carrying the section being lowered exteriorly of the derrick, and guards for protecting the said carrying means. 110

4. A well rigging of the class described including a derrick, means associated with the derrick for simultaneously raising and 115 lowering sections of rods or tubing, an endless cable operating simultaneously with the first mentioned means, and a clamping member carried by said endless cable and adapted to be engaged with the section being lowered, 120 whereby upon the lowering of the said section, the same will be drawn exteriorly of the derrick.

5. A well rigging of the class described 125 including a derrick, a reel positioned adjacent the derrick, pulleys carried by the said derrick, cables oppositely wound upon the said reel and trained over said pulleys whereby to simultaneously raise and lower sections of rods or tubing, and means con- 130

nected with the reel and operated upon rotation thereof for drawing the section being lowered exteriorly of the derrick.

6. A well rigging of the class described including a derrick, a reel positioned adjacent the derrick, pulleys carried by the said derrick, cables oppositely wound upon the said reel and trained over said pulleys, clamping means carried by the free ends of said cables and adapted to engage sections of rod or tubing, means for operating said reel whereby to cause the simultaneous raising and lowering of the said sections, an endless cable trained around said reel and operating therewith, and a hook carried by the said endless cable and adapted to be engaged with the lower end of the section to be lowered, whereby upon the lowering of the said section the same will be drawn exteriorly of

the derrick by the said hook carried by the endless cable and moving therewith.

7. A well rigging of the class described including a derrick, means associated with the derrick for simultaneously raising and lowering sections of rods or tubing, and an endless cable adapted to be engaged with the lower end of the section to be lowered whereby upon the lowering of the said section, the same will be drawn exteriorly of the derrick.

8. A well rigging of the class described including means for simultaneously raising and lowering sections of rods or tubing, and an endless cable operated simultaneously with the first mentioned means for carrying away the sections being lowered.

In testimony whereof I affix my signature.

WALTER D. GILES.
